UNITED STATES PATENT OFFICE.

ALFRED COPONY, OF CHICAGO, ILLINOIS, ASSIGNOR TO WILLIAM H. MINER, OF CHICAGO, ILLINOIS.

YOKE FOR DRAFT-RIGGINGS.

Specification of Letters Patent.

Patented Mar. 9, 1915.

1,131,040.

Application filed March 23, 1914. Serial No. 826,806.

To all whom it may concern:

Be it known that I, ALFRED COPONY, a subject of the Emperor of Austria-Hungary, residing in Chicago, in the county of Cook, 5 and State of Illinois, have invented a new and useful Improvement in Yokes for Draft-Riggings, of which the following is a specification.

This invention relates to improvements in 10 yokes for draft riggings.

It has hitherto been the general custom to make draft yokes of wrought iron which are either riveted to the draw-bar or to a connecting hood or box which in turn is 15 keyed to the draw-bar. As is well known, wrought iron affords great resistance under tension and for this reason is desirable for draft yokes, but where the yoke is riveted to the draw-bar or to a connecting hood, 20 the portions of the metal in front of the rivets and directly adjacent thereto are placed under compression when the gear is operated, with the result that the wrought iron is upset and distorted and the connection thereby impaired. Cast steel yokes 25 have been provided to overcome some of the defects of the wrought iron yokes and to provide a detachable key connection with the coupler, but such yokes are relatively 30 expensive and are not adapted to withstand sharp blows nor are they as reliable under tension or pull as wrought iron yokes. It also sometimes happens that cast steel yokes 35 are defective, due to blow holes therein, which defects are not apparent from an inspection thereof and only come to light when the yoke is in use, thereby incurring considerable danger in the operation of trains.

40 One object of my invention is to provide a yoke composed partly of wrought iron and partly of steel castings which will embody all the advantages of the wrought iron and cast steel yokes without the defects of each.

45 Another object of the invention is to provide a yoke of the type above indicated which extends horizontally and which may be keyed to the coupler.

50 The invention furthermore consists in the improvements in the parts and devices and in the novel combinations of the parts and devices herein shown, described or claimed.

In the drawing forming a part of this

specification, Figure 1 is a side elevation 55 of a yoke embodying my improvements. Fig. 2 is a top plan view of the structure shown in Fig. 1. Fig. 3 is a vertical section taken on the line 3—3 of Fig. 2, and Fig. 4 is a rear end elevation of the yoke.

60 In said drawing, the yoke is shown as comprising two straps of wrought iron 10, 10 each of which has its end portions 11, 11 slightly offset in both vertical and horizontal directions from the main portions 65 thereof, the offset portions 11, 11 being extended through parallel slots 12, 12 in two end pieces 13, 13 of cast steel, the ends of the offset portions 11, 11 of the wrought iron straps being upset as shown at 14, 14 70 to properly and rigidly secure the cast steel pieces and the straps together. Each cast steel piece 13 is provided with a longitudinally extending key slot 15 adapted to receive the coupler connecting key. The steel 75 castings 13 are furthermore beveled on their inner faces as shown at 16 to thereby permit the yoke to swing or tilt relatively to the coupler. To properly hold the two wrought iron straps together at the rear end and to 80 furthermore provide a filler to abut the rear follower, a wrought iron clip 17 is provided, the ends 18 of which are bent over and around the upper and lower edges of the straps to firmly secure them together as 85 shown most clearly in Figs. 1 and 4.

From the preceding description, it will be seen that I have provided a yoke of great strength which possesses all the advantages of an ordinary wrought iron yoke and a 90 cast steel yoke which is free from the defects of each; the wrought iron straps are secured to the cast steel pieces without the use of rivets or other devices which are easily sheared; the yoke may be detachably 95 connected to the draw-bar by means of a key and without the necessity of a hood or box-like head such as hitherto has been used; and the yoke is such that it may be used in a horizontal position while at the 100 same time being detachably connected to the draw-bar.

Although I have herein shown and described what I now consider the preferred embodiment of my improvements, yet it 105 will be understood that various changes and modifications may be made without departing from the spirit of the invention, and

all such changes and modifications are contemplated as come within the scope of the claims appended hereto.

I claim:

5. 1. A horizontal yoke for railway draft rigging having the arms thereof made of wrought iron, the arms having secured thereto at the ends, separate slotted cast steel members through which the ends of the
- 10 yoke arms pass, the ends of the yoke arms being upset to secure the castings in place, substantially as specified.
- 15 2. A yoke of the character described comprising two straps of wrought iron bent to form the arms and rear of a yoke, and slotted steel castings secured to the ends of said straps, the ends of the straps extending through the slots and being headed to unite the parts, said castings being slotted
- 20 to receive a coupler-connecting key, substantially as specified.
3. A horizontal yoke for railway draft

gears consisting of two wrought iron straps bent to form the arms and rear of a yoke, the free ends of said straps being spaced 25 apart in a vertical plane, and slotted steel castings secured to the ends of said straps, the ends of said straps being upset whereby the castings are held in place on the straps.

4. A combined wrought iron and cast 30 steel horizontal yoke for railway draft gears comprising two separate, vertically arranged steel castings slotted to receive a coupler connecting key and wrought iron straps, the wrought iron straps and castings being 35 rigidly connected to each other by integral interengaging portions, the ends of said straps passing through slots in said castings.

Signed this 13th day of March, 1914, in the presence of two witnesses.

ALFRED COPONY.
